United States Patent Office

Des. 223,727

Patented May 30, 1972

223,727

HARP

Henry Levin, 80 St. Marks Place,
New York, N.Y. 10003

Filed Aug. 19, 1970, Ser. No. 24,581

Term of patent 14 years

Int. Cl. D17—03

U.S. Cl. D56—1

FIG. 1 is a top plan view of a harp, showing my new design;

FIG. 2 is a side elevational view;

FIG. 3 is an end elevational view; and

FIG. 4 is an opposite end elevational view thereof.

The bottom, not shown, is substantially flat and unornamented.

I claim:

The ornamental design for a harp, substantially as shown and described.
